UNITED STATES PATENT OFFICE.

MARCEL KÜNZER, OF LA CHAUX-DE-FONDS, SWITZERLAND, ASSIGNOR TO SOCIÉTÉ ANONYME POUR L'EXPLOITATION DES BREVETS KÜNZER, OF BALE, SWITZERLAND.

APPARATUS FOR LIGHTING THE LANDING PLACE FROM AERIAL CRAFT.

Application filed December 11, 1925, Serial No. 74,833, and in Switzerland November 4, 1925.

In many cases aerial crafts are obliged to land in the dark on a ground wholly unknown. The landing must be effected in some minutes and it is therefore very important to light up the landing place from the aerial craft in the space of a few seconds in order to let the pilot of the craft recognize the nature of the ground above which he is moving.

10 The present invention relates to an apparatus for lighting in an effective manner a landing place when said apparatus is ejected from an air craft passing over the country. To this end the apparatus comprises a folded 15 parachute which is unfolded at a predetermined time while lighting a rocket or luminous bomb attached to the apparatus. Preferably the center of gravity of the apparatus is very little above the luminous charge 20 so that this latter is always at the bottom while the apparatus is falling. The parachute is attached at the top of the apparatus.

The annexed drawing represents a working example of the apparatus according to 25 the present invention.

Fig. 1 is a vertical section,

Fig. 2 is a sectional plan on line II—II of Fig. 1 and

Fig. 3 is a detail view.

30 The apparatus comprises an outer shell 81 having a shape best adapted for overcoming the atmospheric resistance. This shell is divided into a number of chambers separated by partition walls 82, 83 and 84. An 35 open cylinder 183 placed above the wall 82 encloses a folded parachute 184 which is attached to the upper edge of the shell by the ropes 85. A helical spring 86 arranged at the bottom of said cylinder carries a 40 piston 87 and after having been bent is adapted to eject the parachute.

A rod 187 fast to the piston provided with a hook 88 projects downwards from below said piston and forms the means for maintaining the spring in a bent state and the piston ready for ejecting the parachute. When spring 86 is in an unbent state piston 87 may be pressed down by means of a knob 90 and rod 187 may be thrust through the 50 opening 89 until by a turn given to piston 87 hook 88 has clasped the wall 82.

The chamber between the walls 82 and 83 contains a clockwork whereof only the principal parts, the barrel 91 and the regulator

92 are represented. The arbor of the barrel 55 has a lengthening like a crank 94 which on its path meets the nose 88 of rod 187 so as to turn it until it touches a check piece 95. In this position the rod hook under the effect of spring 86 slips through a slot 60 in the wall 82 and releases the piston so as to eject the parachute. The moment of this operation may be predetermined by means of a crank 96 moving on a graduation 65 97 on a plate 200 of the clockwork. Owing to a bevel gear 98 establishing the working connection between the arbor of the barrel and the shaft of the crank 96 the bending of the spring in the barrel is depending upon the position of the crank on the graduation 70 which will determine also the time of ejecting the parachute which will take place when said cranks have assumed again their zero position. After the clockwork has been set 75 going and the stop 198 has released the plate 99 the crank 94 as well as the crank 96 will tend to assume again their initial position of zero. Said stop 198 is operated by hand and may be constructed as shown. It serves as a safety device against accidents due 80 to careless handling while the apparatus is not in use. When the apparatus is taken into use said stop 198 is removed after having adjusted the crank 96.

The space between the walls 83 and 84 is 85 filled with a heat-insulating, fire-proof substance 100 and is arranged above the chamber 101 containing a flare body. When this charge is lighted the luminous vapours will escape through the slots 102. The lighting 90 charge communicates through a canal 104 across the insulating substance with a tube 103 provided with a cartridge primer 105 which can be fired by a hammer 106. This hammer can be cocked by means of a lever 95 107 extended to the outside of plate 200. A helical tension spring fast to plate 110 is attached to the lever 107 which is linked to the striking arm of the hammer and pivoted 100 within a slot of plate 200. The cocked hammer is maintained in its position by means of lever 111. This lever is pivoted on a vertical pin fast to plate 110 and is kept by means of a curved arm and under the effect of a spring not shown in sliding contact 105 with the cylindrical surface of the barrel 91. The other arm is shaped like a hook 108 and extends into the path of the tail end of ham-

mer 106 which is pivoted on a standard 115. Said tail end of the hammer is curved in such a way that when the hammer is cocked by raising its striking arm by means of 5 lever 107 the hook 108 snaps over said tail end of the hammer and maintains it in its cocked position. The cylindrical surface of the barrel is also swept by a finger 115 at the end of an arm 116 fast to the barrel's 10 axle. When the crank 96 which is the controlling means of the apparatus has returned to its zero position and when the parachute has been ejected from the cylinder 183 then also arm 116 will have reached its initial 15 position and finger 115 will have met with and have passed the curved end of lever 111. This lever will be swung out thereby and hook 108 will be withdrawn from the tail end of hammer 106 which will strike down 20 on the cartridge primer and will fire the flare body within chamber 101, hook 108 will release the hammer 106 which under the effect of spring 109 strikes the cartridge primer and lights the lighting charge. 25 Tube 103 is mounted on a small slide 113 which can be reached through a door 114. If this slide according to Fig. 2 is pushed to the right tube 103 its cap will be withdrawn out of reach of hammer 106. In 30 this position not only canal 104 is shut but any undesired firing of the cap is made impossible.

If the apparatus is not in use the parachute is held down inside of cylinder 183 35 by two arms 120 hinged within slots to the walls of said cylinder. In the drawing one arm is shown in an upright and the other arm in a turned down position. Instead of being arranged so as to operate simultaneously 40 the ejecting of the parachute and the firing of the charge could be arranged to operate at different times. Also the means employed could be other than those shown. Thus an aerial propeller or turbine could be 45 employed which would operate a certain time before the firing would do so. Also the

cartridge priming could be mounted on a disk which would be turned by the aerial propeller attached to the apparatus before its ejection and would turn so as to operate 50 the firing after a certain height of fall.

Also an electric battery could be provided inside of the apparatus and the current be employed for creating a spark for firing the lighting load. The chamber 101 containing the lighting load could also be arranged so that it would, when fired, be separated from the apparatus and would drop first quite independently from the other parts. The lighting charge would 60 then be dropped and burn in the free air.

With such an apparatus it is possible to reach a determined height in a very short time, to unfold there the parachute in order to slaken the velocity of fall and to light 65 the lighting charge simultaneously or somewhat before. By such a proceeding the apparatus floats at the proper distance from the country which is to be lit up and allows thereby to have in a few minutes a prospect 70 of the conditions of the landing.

What we claim is:

In an apparatus for lighting the landing place from aerial crafts the combination of 75 an open cylinder turned upwards and an outer shell attached to said cylinder so as to form a chamber underneath said cylinder, a folded parachute sheltered within said cylinder and attached to said shell, an ejecting device for the parachute constituted of a 80 spring operated piston, a clock work contained within said chamber and a flare body suspended at the bottom of said shell, a firing device comprising a cocked hammer and a cartridge primer at an effective distance from said flare and a releasing mechanism consisting of cranks controlled by said clockwork and adapted to release the spring operated piston and the cocked hammer of 85 the firing device.

In testimony whereof I affix my signature.
MARCEL KÜNZER.
